UNITED STATES PATENT OFFICE.

JOHN NORMAN YOUNG, OF BROCKVILLE, ONTARIO, CANADA.

MOP-HEAD.

972,315.

Specification of Letters Patent. Patented Oct. 11, 1910.

Application filed April 11, 1910. Serial No. 554,878.

To all whom it may concern:

Be it known that I, JOHN NORMAN YOUNG, of Brockville, in the Province of Ontario, Dominion of Canada, have invented certain new and useful Improvements in Mop-Heads, of which the following is a specification.

My invention relates to improvements in mop heads, and the objects of my invention are to provide a simple and effective form of mop head which may be cheaply manufactured and which will firmly and effectively hold the mop cloth in position, but which will nevertheless be readily removable when desired.

It consists essentially of the improved construction hereinafter described in detail in the accompanying specifications and drawings:

20 In the drawings: Figure 1 is a perspective view of the mop head with the cloth thereon. Fig. 2 is a side view of the mop head.

In the drawings, like characters of reference indicate corresponding parts in each figure.

Referring to the drawings, A represents a mop handle of usual construction and B the supporting member for the mop cloth which is in the form of a substantially rectangular frame having means for attaching it to the mop handle. This frame member is formed of wire and the means for attaching it to the handle comprise a plurality of spiral turns 10 formed in the supporting member and adapted to encircle the mop handle, a loop 11 being also formed on the uppermost of said turns and through this loop a fastening screw 12 may be inserted.

The front side 13 of the supporting member extends substantially at right angles to the mop handle and is adapted to support the mop cloth in operative position. To hold the mop cloth against the side 13, a retaining member C is provided, preferably of resilient material having one free end 14. This member is adapted to extend substantially parallel with the side 13. In accordance with the present invention, this member is formed integral with the supporting member, the whole being thus formed of a

single piece of wire, one end 14 of which forms the end of the retaining member while the other end 15 is bent upwardly at the end of the side 13 and formed with a loop 15 which encircles the upper side 17 of the retaining member.

To hold the retaining member in closed position, a link member 18 is provided slidably mounted on the supporting member and adapted to engage the end 14, said end 60 for convenience in locking may be enlarged at the extremity as by turning a portion of the wire back on itself.

It will thus be seen that the present invention provides an exceedingly simple and effective form of mop head, the material and construction of which is very cheap, and owing to the absence of machine work, the labor costs are very small. There are no corners or other projections likely to engage 70 or scrape the floor, and the mop head possesses many advantages in practical use over those previously constructed.

As many changes could be made in the above construction, and many apparently 75 widely different embodiments of my invention within the scope of the claims could be made without departing from the spirit or scope thereof, it is intended that all matter contained in the accompanying specifications 80 and drawings shall be interpreted as illustrative and not in a limiting sense.

What I claim as my invention is:

1. A mop head comprising a supporting member in the form of an oblong wire frame 85 having a plurality of spiral turns adapted to encircle the mop handle, one end of the wire extending to form a retaining member adapted to hold the mop cloth against the front side of the supporting member, and means for holding the retaining member in closed position.

2. A mop head comprising a supporting member formed of a substantially rectangular frame of wire having parallel front 95 and upper sides which are adapted to extend at substantially right angles to the mop handle, the end of the front side being turned upwardly and formed with a loop encircling the upper side, a retaining mem- 100

ber formed by an extension of the wire forming the supporting member and extending substantially parallel with the front side of the supporting member, and a link mounted on the supporting member adapted to engage the end of the retaining member to hold it in closed position.

In witness whereof I have hereunto set my hand in the presence of two witnesses.

JOHN NORMAN YOUNG.
